UNITED STATES PATENT OFFICE.

WILLIAM M. VISER, OF LOUISVILLE, KENTUCKY.

DESIGN FOR A PUBLIC TRASH RECEPTACLE.

Application filed March 25, 1922. Serial No. 1,395. Term of patent 14 years.

To all whom it may concern:

Be it known that I, WILLIAM M. VISER, a citizen of the United States, residing at Louisville, in the county of Jefferson and State of Kentucky, have invented a new, original, and ornamental Design for Public Trash Receptacles, of which the following is a specification, reference being had to the accompanying drawing, forming part thereof.

The figure is a perspective view of a public trash receptacle showing my new design.

I claim:

The ornamental design for a public trash receptacle substantially as shown.

In testimony that I claim the foregoing as my own, I have hereto affixed my signature.

WILLIAM M. VISER.
